THERMOSTATIC CIRCUIT BREAKER WITH
CONTACT ARC PREVENTIONTownsend M. Gunn, Attleboro, Mass., assignor to
Metals and Controls Corporation, Attleboro,
Mass., a corporation of Massachusetts

Application May 12, 1945, Serial No. 593,406

5 Claims. (Cl. 175—294)

1

This invention relates to thermostatic circuit breakers and more particularly to such circuit breakers for across the line operation with contact arc prevention.

Among the objects of the invention are the provision of a circuit breaker which may be made small and compact; the provision of a circuit breaker for across the line operation adapted to interrupt heavy currents; the provision of a circuit breaker of the type indicated which may be easily calibrated during manufacture; the provision of a circuit breaker which has a long life; and, the provision of a circuit breaker which may be easily constructed of few and inexpensive parts. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawing, in which one of various possible embodiments of the invention is illustrated,

Fig. 1 is a top plan of the device with the cover broken away;

Fig. 2 is a section taken on line 2—2 on Fig. 1;

Fig. 3 is a section taken on line 3—3 on Fig. 1 and showing the parts in different operating positions; and,

Fig. 4 is a section similar to Fig. 3 but showing the parts in still different operating positions.

Similar reference characters indicate corresponding parts throughout the several views of the drawing.

Referring now to the drawing, the circuit breaker of the present invention is shown in Figs. 1 and 2 in closed circuit position. The device includes a base 1 and a cover 3. Mounted in base 1 are terminals 5 and 7 which carry respectively stationary line contacts or terminals 9 and 11. Mounted on bosses 12 on base 1 by means of bolts 13 are spring arms 15 and 17 which carry at their opposite ends, respectively, movable shunt contacts 19 and 21. Spring arms 15 and 17 normally locate contacts 19 and 21 above contacts 9 and 11, arm 15 biasing contact member 19 away from terminal 9 and arm 17 biasing contact member 21 away from terminal 11. A hub 23 is formed on base 1 on which is mounted a snap-acting thermostatic disc 25 of the type shown and described in Spencer patent 1,448,240. Disc 25 is loosely mounted at its center by a pin 27 and carries at opposite points on its edge, disc

2

or auxiliary contacts 29 and 31. Pin 27 prevents rotation of disc 25 on pin 27 and locates contact 29 above contact 19, and contact 31 above contact 21. A cavity 33 is formed in base 1 to accommodate a shunt resistance 35 connected between the two posts 13 which mount spring arms 15 and 17. Brackets 37 are mounted on base 1 and carry adjusting screw stops 39. Screws 39 are located above spring arms 15 and 17 to act as limiting stops therefor. Terminals 5 and 7 are connected respectively to power line leads 41 and 43.

When the device is in the position of Figs. 1 and 2, current passes through lead 41, terminal 5, contact 9, sandwiched contact 19, contact 29, disc 25, contact 31, sandwiched contact 21, contact 11, terminal 7 and lead 43. Resistance 35, which is of a relatively high value, is at this time in shunt or parallel around disc 25 (see parts 15, 17, 13 and 35).

If the current passing through the device increases to an undesirably high value, the passage of the current through disc 25 heats it until it snaps from its non-overload position bowed toward terminals 9 and 11, as shown in Fig. 2, to its overload position bowed away from the terminals, as shown in Fig. 4, passing through the stage shown in Fig. 3. The resilient force of disc 25, which in its Fig. 2 position sandwiched contact 19 between contacts 9 and 29, and contact 21 between contacts 11 and 31, is removed by this change in curvature. The resilience of arms 15 and 17 thereupon separates contact 19 from contact 9 and contact 21 from contact 11. The parts momentarily assume the positions shown in Fig. 3 in which the contacts 19 and 21 momentarily follow contacts 29 and 31, respectively. This condition continues until the stops 39 are reached by the spring arms 15 and 17. The disc 25 then continues to move, thereby advancing the contacts 29 and 31 away from the contacts 19 and 21, respectively (Fig. 4). In the Fig. 3 position current may tend to arc from 9 and 11 to 19 and 21, respectively, and then pass partly through the disc and partly through the resistance. As the contacts 29 and 31 first separate from contacts 19 and 21, respectively (under the Fig. 4 conditions) and before ionization takes place between them, the resistance is high in the disc part of the parallel arms of the circuit constituted by the disc 25 and the resistance 35.

The current path is thereby established through resistance shunt 35. Thus little or no arcing occurs between contacts 19 and 29 and 21 and 31, respectively. The high value of resistance 35

also inhibits arcing between contacts 9 and 19 and 11 and 21, respectively. Thus the device assumes the position shown in Fig. 4, the circuit between lines 41 and 43 having been broken with little or no arcing taking place between any pair of contacts. In this connection it should be noted that, in addition to the advantageous mechanical functions asserted above for a given group of co-operating contacts such as 9, 19, 29 or 11, 21, 31, substantially simultaneously compounding the functions of both in electrical series (relative either to the resistance 35 or disc 25) results in further reducing the tendency to arc formation.

The position of stops 39 is adjustable to vary the relative separation between contacts 9 and 19, and 11 and 21 on one hand and between contacts 19 and 29, and 21 and 31 on the other.

Contacts 19 and 21 may be made large in size, if desired to act as arc coolers and further to tend to snuff out any arcs which may form.

In the drawing the circuit breaker is shown as of the automatic type. Disc 25 is constructed so that after the circuit is interrupted disc 25 cools and snaps back to its Fig. 2 position. This again sandwiches contact 19 between contacts 9 and 29 and contact 21 between contacts 11 and 31, reclosing the circuit first described above. If the fault in the circuit which caused the passage of the undesirably high current through disc 25 still exists, the above described cycle will be repeated until the fault is corrected.

If a manual resetting circuit breaker is desired, disc 25 is merely constructed with a different temperature differential so that it does not snap back to its Fig. 4 position upon cooling to normal ambient temperature, but must be manually pushed to its Fig. 2 position. A handle is then located in cover 3 above disc 25 so as to press on the edges of disc 25.

The circuit breaker of the present invention may be used to interrupt currents of a thousand amperes or over without substantial danger to the contacts. Currents of such sizes are normally highly disruptive of circuit breaker contacts because of arcing between the separated contacts. The circuit breaker of the present invention, on the other hand, practically eliminates arcing between any pair of the contacts, and therefore the contacts may be made smaller than would otherwise be possible. Moreover, inhibition of arcing makes it possible to use the circuit breaker for long periods of time without repair or replacement.

The circuit breaker of the present invention may be used in lieu of fuses to protect house lighting circuits. If an automatic circuit breaker such as described herein is employed, the breaker needs no attention and has a long period of usefulness. If the breaker of the present invention is made to require manual resetting it still avoids the necessity for replacing burnt out fuses, which may not be readily available.

Accordingly it will be seen that a circuit breaker is provided which breaks a circuit by first switching in a shunt circuit and then switching itself and the protecting shunt circuit out of the line to open the circuit.

In view of the above, it will be seen that the several objects of the invention are achieved and other advantageous results attained.

As many changes could be made in the above construction without departing from the scope of the invention, it is intended that all matter contained in the above description or shown in

the accompanying drawing shall be interpreted as illustrative and not in a limiting sense.

I claim:

1. A thermostatic circuit breaker comprising line terminals for connecting the circuit breaker in a line, a contact member movable toward and away from one of said terminals and biased away from said one terminal, an electrically conductive, thermostatically actuated element movable from a non-overload to an overload position in response to current overload in the line, said element in its non-overload position engaging and holding said contact member against said one terminal and completing a circuit from one side of the line through said contact member and element to the other side of the line, said element moving away from said one terminal in moving to its overload position, an electrical resistance connectible with the other side of the line through said contact member, and a stop positioned to limit movement of the contact member away from said one terminal for disengagement of said contact member and electrically conductive element when the latter moves to its overload position.

2. A thermostatic circuit breaker comprising line terminals for connecting the circuit breaker in a line, a contact member movable toward and away from one of said terminals and biased away from said one terminal, a snap-acting, electrically conductive thermostatic element adapted to snap from a non-overload to an overload position upon heating in response to flow of overload current therethrough, said element in its non-overload position engaging and holding the contact member against said one terminal and completing a circuit from one side of the line through said contact member and element to the other side of the line, said element moving away from said one terminal in moving to its overload position, an electrical resistance connectible with the other side of the line through said contact member, and a stop positioned to limit movement of the contact member away from said one terminal for disengagement of said contact member and electrically conductive element when the latter moves to its overload position.

3. A thermostatic circuit breaker comprising line terminals for connecting the circuit breaker in a line, contact members movable toward and away from the terminals and biased away from the terminals, an electrically conductive, thermostatically actuated element movable from a non-overload to an overload position in response to current overload in the line, said element in its non-overload position engaging and holding said contact members against the terminals, said element moving away from the terminals in moving to its overload position, an electrical resistance connecting the contact members, and stops positioned to limit movement of the contact members away from the terminals for disengagement of the contact members and element when the latter moves to its overload position.

4. A thermostatic circuit breaker comprising a base, a pair of line terminals on the base, a pair of contact members mounted on the base for movement toward and away from the respective terminals and biased away from the terminals, a snap-acting, electrically conductive thermostatic element adapted to snap from a non-overload to an overload position upon heating in response to passage of overload current therethrough, said element being mounted on the base in such relation to the terminals and contact

members as to engage the contact members and hold them against the terminals when in its non-overload position, thereby to complete a circuit between the terminals, said element moving away from the terminals to release the contact members upon snapping to overload position, an electrical resistance connecting the contact members, and stops mounted on the base positioned to engage the contact members and limit their movement away from the terminals for disengagement of the contact members and thermostatic element when the latter has snapped to overload position.

5. A thermostatic circuit breaker comprising a base, a pair of line terminals fixed on the base, a pair of spring arms mounted on the base carrying contacts movable toward and away from the respective terminals, the arms tending to move the contacts away from the terminals, a snap-acting, dished thermostatic disc mounted on the base having a pair of contacts engageable with the movable contacts, said disc being electrically conductive and adapted to snap from a non-overload position bowed toward the terminals to an overload position bowed away from the terminals upon heating in response to passage of overload current therethrough, said disc being located on the base for engagement of its contacts with the movable contacts to hold them against the terminals when the disc is in non-overload position, and for releasing said mov-

able contacts upon snapping to overload position, an electrical resistance connecting said movable contacts through said spring arms, and a pair of stops mounted on the base in position to engage the spring arms to limit their movement away from the terminals for disengagement of the movable contacts and the contacts on the disc when the disc has snapped to overload position.
